UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

GARMENT.

Application filed February 8, 1922. Serial No. 535,085.

To all whom it may concern:

Be it known that I, VICTOR GUINZBURG, a citizen of the United States, and a resident of the city, county, and State of New York, have invented a certain new and useful Improvement in Garments, of which the following is a specification.

This invention relates to a form of under-garment, the purpose of which is to act as a carrier or support for a pair of dress shields to obviate the necessity of sewing a pair of dress shields into a waist or other outer garment worn by a woman and the object of this invention is to provide a garment of this character which will fit snugly, thus holding the shields in their proper position; which will be of very sheer material so that it will not be visible through the light and thin outer garments worn at the present time; which will not be provided with unnecessary fastening means to thicken or increase the bulk of the garment worn by women.

A further object of this invention is to provide a garment of the character above mentioned to be used as a foundation or support for dress shields and which will be provided with attached or integral adjusting means at the waist or neck openings whereby the garment will fit perfectly and snugly persons of various measurements.

With these objects and other objects which may hereinafter appear in view, I have devised the particular arrangement of parts hereinafter set forth and more particularly pointed out in the claims appended hereto.

Reference is to be had to the accompanying drawing forming a part hereof in which

Figure 1 is a front elevation of a garment made in accordance with my invention, and

Figure 2 is a fragmentary view of a portion of the garment adjacent one of the openings showing the manner in which the elastic garment contracting strip is secured in place.

Throughout the various views of the drawings, similar reference characters designate similar parts. In the preferred embodiment of my invention as disclosed in the accompanying drawing, the front portion of the body of the garment is indicated at 1 and the rear portion 2. The garment is completely enclosed, that is, it is not provided with a front or rear opening of any sort which would necessitate the use

of cumbersome fastenings which might be undesirable in a garment of this kind. The garment is preferably of an open mesh netted fabric so that the same will be very sheer and extremely light in weight and not visible when in use.

At 3 are shown the sleeves which are substantially short and of the same netted material as the body of the garment. At 4 are shown the shields which are permanently affixed to the garment at the arm pits so that they form a unitary part of the garment.

The garment is provided with an expandable neck opening 5 and a waist opening 6 each of said openings being expanded and contracted by means of an elastic strip 7 secured about the edge of the opening by means of over-stitching 8 which passes through the openings in the net of the body.

To permit expansion of the openings 5 and 6, they are gathered or Shirred as at 9 and 10, surrounding the elastic contracting strips 7. This permits the garment to expand at the openings without any undue strain being placed upon the netted fabric of the body at those points. The manner in which the elastic cords or strips 7 are secured in place by over-stitching passing through the openings in the netted fabric retains it securely in place and when it stretches, it stretches each portion of the netted fabric body evenly whereby the garment is caused to fit the wearer perfectly adjacent the openings and all undue strain on the body of the garment adjacent the expandable openings is avoided.

The form of garment herein disclosed provides a garment in which the dress shields are held snugly in position; its shoulder portions 11 prevent the garment from sliding from the shoulders as is one of the disadvantages of shield carrying garments in use at the present time.

The garment being made of an open mesh netted fabric permits it to be worn comfortably in warm weather; to appear substantially invisible when used and to be washed with the shields which form an integral or unitary part of the garment.

From the foregoing it is obvious that my invention is not to be restricted to the exact embodiment shown but is broad enough to cover all structures coming within the scope of the annexed claims.

What I claim is:—

1. An article of the class described comprising a garment having a body of an open-work netted material, said garment having a neck, waist and arm openings, sleeves of open-work netted material secured to said body at said arm-openings, and shields secured in said sleeves and in the armpit portions of said garment body.
- 10 2. An article of the class described comprising a garment having a body of an open-work netted material, said body being

provided with a neck and a waist opening, an elastic strip extending about and along the edge of one of said openings and secured thereto by stitching extending over said strip and through the openings in the open-work netted material, the body material about said last mentioned opening being gathered.

Signed at the city, county and State of New York this 6th day of February, 1922.

VICTOR GUINZBURG.
